CORROSION RESISTANT AEROSOL PACKAGE
CONTAINING HYDROLYZABLE MATERIALRichard L. Riley, Laurel, Md., assignor to Chempel Inc.,
Camden, N.J., a corporation of New Jersey

No Drawing. Filed Nov. 13, 1956, Ser. No. 621,506

10 Claims. (Cl. 206—6)

This is a continuation-in-part of my application Serial No. 562,953, filed February 1, 1956, now abandoned.

This invention relates to chemical compositions under pressure which contain propellants for discharging them from a container through a dispensing valve into the atmosphere.

Since the advent of the so-called "aerosol bomb" devised by Goodhue and Sullivan (see U.S. Patent No. 2,321,023), many attempts have been made to find substitutes in whole or in part for the expensive Freons employed as the propellant. The use of Freon alone has the important advantage that the pressure in the container remains substantially constant as the liquid is discharged, thereby giving substantially uniform conditions of dispensing. The Freon is also important as the boiling solvent of the composition and hence cannot be dispensed with entirely in cases where the compositions to be dispensed are to assume a particle size smaller than what can be provided by a wet spray, because the violent boiling of the Freon upon escape to the atmosphere is depended upon to break up the sprayed droplets into even smaller particles. For this purpose, however, it is not necessary, or at least not always necessary, to use large quantities of the Freon, such as in the case when Freon is used as the sole propellant. As a result, constant efforts have been made to find a substitute for at least a portion of the Freon and one such effort has resulted in the use of carbon dioxide.

Accordingly, carbon dioxide has been used in some cases in combination with Freon as a propellant assistant. This, in accordance with the prior art, is done by either charging the container with carbon dioxide gas directly or by the insertion of pellets of solid carbon dioxide (Dry Ice) in the container just before the containers with the usual dispensing valve are hermetically sealed. The solid carbon dioxide soon sublimes into its gaseous form, a portion of which may become dissolved in the liquid phase of the composition.

One of the objects of this invention is the provision of a novel method of providing carbon dioxide gas as a propellant assistant for Freon in compositions of the type mentioned.

A further object of the invention is the provision of a composition of matter adapted to be stored under pressure in a hermetically sealed container.

A still further object of the invention is the reduction in the cost of providing compositions of matter containing propellant gases.

A further object of the invention is to provide aerosol compositions in which water is substituted for a substantial portion of organic solvents previously employed. The cost of manufacturing the composition is accordingly substantially reduced. The nature of the compositions provided by this invention are such that water may be employed as a component along with components such as

2

Freon-11, methylene chloride and alcohols, the use of which in the past with water was avoided due to the corrosive action developed by such compositions which seriously affected their shelf-life in metal containers.

5 A further advantage of the invention is to provide a composition of the kind described in which water is used, and in which corrosive action is avoided, and in which the substantial proportion of water makes it feasible to absorb sufficient amounts of carbon dioxide to serve as a propellant assistant. The use of carbon dioxide as a propellant assistant aids, in some cases, in making it feasible to reduce the amount of fluorinated hydrocarbon (Freon, Isotron, Genetron) which is also employed as a propellant, and thereby in effecting additional savings in the cost of manufacturing the compositions.

10 A further purpose of the invention is to provide non-corrosive aerosol compositions employing a substantial proportion of water in which carbon dioxide is employed as a propellant assistant, and which are capable of maintaining the spraying pressure throughout the shelf-life of the composition which at a minimum is from 15 to 20 months.

15 A further object of the invention is to provide aerosol compositions which comprise an aqueous phase and an organic liquid phase which have substantially similar densities, so that emulsification of the entire composition can be readily attained.

20 A further object is to provide such compositions which are noncorrosive with respect to tin lined metal containers and in which substantial amounts of carbon dioxide may be dissolved to serve as a propellant assistant.

25 A further important object of the present invention is to provide aerosol compositions which contain a substantial amount of water and methylene chloride, Freon-11 or other organic components which are known on hydrolysis to produce corrosive products and which nevertheless are noncorrosive with respect to tin lined metal containers.

30 35 It is also an object of the present invention to provide aerosol compositions which employ substantial amounts of water and also alcohols which in past practice have been avoided in compositions comprising water because of the resulting corrosive action on metal containers.

40 45 All of these foregoing objects are accomplished in the compositions which are described hereafter in the specific examples.

The term "propellant" as used herein without any further designation is to be construed as meaning one or more of the low boiling point fluorochlorohydrocarbons which are commonly employed as aerosol propellants. The term "propellant" also includes mixtures of these hydrocarbons as well as other commonly known aerosol propellants such as methyl chloride, etc. It will also be understood that the "propellant" will cover mixtures of the compounds mentioned above with vapor pressure modifying components such as methylene chloride, methyl chloroform and similar blends of compounds which are known in the art. The term "propellant assistant" is

50 55 60 65 70 meant to designate gases such as carbon dioxide and nitrous oxide which are not condensable at pressures and temperatures ordinarily encountered in aerosol products. Among the fluorochlorohydrocarbons such as contemplated by the above definition of propellants are the compounds sold generally under the trade designations of "Freons," "Genetrons" and "Isotrons." Most commercial aerosol products employ propellants which at room temperature have a vapor pressure of 40 to 70 pounds per square inch and the present invention is accordingly

concerned in large degree with propellants exhibiting vapor pressures in this range.

In accordance with one form of the present invention, a portion of the Freon is substituted by an unreacted mixture of water, sodium and/or potassium bicarbonate, and an acid which can react with the bicarbonate to generate carbon dioxide. The preferred procedure is to place in an open container, equipped with the usual discharge or dispensing valve, a quantity of the material to be dispensed therefrom and also a given quantity of water together with the bicarbonate and acid in dry form. The preferred procedure in some cases is to dissolve the bicarbonate in a portion of the water which is to be used in making up the composition and then adding the acid in tablet form, for example in the case of citric acid. In other instances, both the citric acid and the bicarbonate have been predissolved in separate portions of the water which is to be employed. The container is promptly sealed after the above-named components are added, and liquefied Freon is forced into the sealed container under hydraulic pressure through the valve. When both the bicarbonate and acid are added in solution form, the bicarbonate solution is fed into the sealed can through the valve just prior to Freon.

A preferred acid is citric acid, although other acids may be used so long as they are compatible with the other ingredients and will not adversely affect persons or objects to be subjected thereto. Accordingly, acids like acetic, citraconic, itaconic, tartaric, malic, maleic, fumaric, succinic, and adipic, may be used in specific instances.

The invention is useful in all the various types of propellant compositions now in commercial use, such as insecticides, perfumants, paints, cleaners, plastics, artificial snow producing compositions, deodorants, hair sprays, etc.

For pressure in the range of 40 to 70 pounds per square inch, the amount of bicarbonate used will usually be in the range of about 1 to 5% with a stoichiometric quantity of the acid or a small excess thereof to insure utilization of all the bicarbonate. However, there is no critical limit and any desired amount of these ingredients may be used depending upon the pressure desired in the container, a great amount giving a higher pressure and a small amount a lower pressure.

An aerosol package as generally described above, and as in each of the following specific examples, has surprising properties of corrosion resistance throughout a long period of shelf-life, a minimum of 15 to 20 months. This is true even through hydrolyzable components such as methylene chloride, Freon-11, etc. are employed in the package along with the substantial amount of water. It has been observed in most cases that such compositions, when placed in commercial grade tin-lined cans, develop on the interior of the can a characteristic gray film. Although the film develops within a short time after the composition is packaged, it is substantially identical to its appearance after the package has been stored for a year or more. Except for the formation of the gray film, the interior of the metal container in which the composition is stored is not otherwise altered and the corrosion and pin-holding of the metal container which ordinarily occurs when hydrolyzable components are employed with water does not develop. This advantageous feature of the present invention may be also achieved in aerosol compositions in which certain of the reaction products of the bicarbonate and citric acid, (or other named salts and acid), are themselves added to the water-containing composition which is thereafter placed in tin-lined metal containers. More precisely, it is only necessary, for example, to add sodium citrate and citric acid to obtain the anticorrosion action. The carbon dioxide may also be added since a propellant assistant is desirable in most instances, as such, and to enhance the anticorrosion properties to a useful degree. The carbon dioxide, when

used, may thus be furnished from an external source as a gas or as a solid, or may be formed in situ, as described above. The presence of the substantial amount of water in the composition enables a useful amount of carbon dioxide to be dissolved and therefore permits replacement of the more expensive fluorohydrocarbon propellant with carbon dioxide. The same advantageous corrosion-resisting properties may be achieved where nitrous oxide is employed as a propellant assistant in lieu of carbon dioxide, although its solubility does not seem to be as great. Nevertheless, the use of nitrous oxide as a propellant assistant may be desirable in some instances. Similarly, the invention is applicable to compositions wherein nitrous oxide and/or carbon dioxide are used as the propellant, and no fluorinated hydrocarbon (Freon, Genetron, Isotron) is employed. For example, it is applicable to edible compositions of the kind which employ a propellant comprising 85% nitrous oxide and 15% carbon dioxide.

The following examples will further illustrate the invention in relation to some of the various types of products which are in commercial use.

Example 1

A deodorant composition in accordance with this invention has the following formula, by weight:

	Percent
Propylene glycol	3.5
30 Triethylene glycol	3.5
Isopropyl alcohol 99	25.0
Methylene chloride	25.0
Water	28.0
Citric acid	1.25
35 Bicarbonate of soda	1.25
Perfume	0.2
Freon 12	12.3
Total	100.00

The composition is prepared by placing in the container to be used, equipped with the usual dispensing valve, the propylene glycol, triethylene glycol, isopropyl alcohol, methylene chloride and water. Just before the container is sealed, dry tablets of citric acid and bicarbonate of soda are dropped into the container. The container is then promptly sealed and the Freon charged into it through the valve mechanism under hydraulic pressure, before the tablets have had time to dissolve in the liquid and react to any substantial extent. Other samples were prepared using the same procedure except that 12.5 parts of the 28 parts of water were used to first dissolve the bicarbonate. The citric acid was in some cases added as a pellet and in others the citric acid was first dissolved in the remaining 15.5 parts of water.

The composition results in a pressure of 60 pounds per square inch at 70° F. and loses only about 10 pounds as the dispensing of the liquid proceeds to completion.

The containers employed in making up these aerosol compositions were conventional six-ounce tin-lined aerosol containers. A number of samples were opened up after more than a year's storage, and the interior of the containers exhibited the gray film described above and showed no evidence of corrosion. Other deodorant compositions were prepared employing the same ingredients as described, except that in lieu of the bicarbonate of soda and citric acid there was added to the composition sodium citrate 2.5%, then citric acid to bring the composition to pH 5.2, and carbon dioxide, as a propellant assistant, was introduced into the containers from an external source to a pressure of about 61 pounds per square inch. Equally good results were obtained with respect to corrosion resistance and the maintenance of spraying pressure.

Example 2

An artificial snow producing composition in accordance with the present invention has the following composition, by weight:

	Percent
Powdered stearic acid	15
Lucite (methyl methacrylate resin)	5
Methylene chloride	25
Water	37
Triethanolamine	0.5
Freon 12	15
Powdered mixture of sodium bicarbonate and citric acid in stoichiometric amounts	2.5
Total	100.0

In this case the bicarbonate and acid were added as a powdered mixture just prior to the hermetical sealing of the container and the charging of it with the Freon. It gave a pressure in the container of 60 pounds per square inch at 70° F. which dropped a maximum of only 10 pounds per square inch during dispensing of the contents.

By changing the composition to provide 34.7% water instead of 37%, and 5% mixture instead of 2.5%, the pressure was increased to 65 pounds per square inch at 70° F. and it was possible to completely dispense the contents of the container.

The above-described snow composition was placed in conventional Crown cans having a tin lining, and after being stored for more than a year no corrosion was observable on the interior of the can. In this instance also, the characteristic gray film appeared on the interior of the can.

Other samples of this artificial snow composition were produced employing the components in the same proportions described above, except that in place of the powdered mixture of sodium bicarbonate and citric acid, the reaction products themselves of this salt and acid were employed, the carbon dioxide being introduced as a propellant assistant from an external supply of carbon dioxide gas. The composition made up in this manner exhibited equally satisfactory corrosion resistance and performance characteristics.

Example 3

An insecticidal composition in accordance with this invention which is particularly effective against flies comprises the following ingredients in the proportions indicated by weight:

	Percent
Pyrethrins	0.2
DDT	3.0
Petroleum distillates	16.8
Methylene chloride	35.0
Water	27.0
Emulsifier	0.5
Freon 12	11.5
Potassium bicarbonate	3.0
Citric acid	3.0
Total	100.0

The composition was prepared similarly to the previous one mentioned in which all but the last three ingredients listed were first placed in the dispensing container, then the potassium bicarbonate and citric acid in dry form. The container was then promptly sealed and the Freon injected into the container through the dispensing valve under hydraulic pressure.

The containers employed were conventional six-ounce cans having a tin lining. The samples were opened after more than a year's storage, and no corrosion had occurred; the formation of a gray film on the interior surface of the can was observed in all samples.

Further insecticide compositions were made employ-

ing the same ingredients as described above, except that the potassium bicarbonate was eliminated and 3% sodium citrate was employed in place of the potassium bicarbonate. Carbon dioxide as a propellant assistant was introduced from an external source of carbon dioxide gas to provide a pressure of about 53 pounds per square inch. Other samples were prepared as described immediately above (using the sodium citrate), except the carbon dioxide was not employed. Further samples were prepared in the same manner as described immediately above, except that nitrous oxide was used as a propellant assistant, this being introduced from an external supply of the gas to provide a pressure of about 66 pounds per square inch.

All samples were placed in both six-ounce and four-ounce conventional containers having a tin lining, and were subjected to accelerated aging tests. At the end of a period of time corresponding to the conventional shelf-life of such products, representative samples were inspected and no corrosion was observed. In each instance the interior of the cans displayed a gray film.

Regarding all of the foregoing examples given above, it was observed that in addition to the density of the water and organic liquid phase being substantially the same, the pH value of the compositions when initially made up was in the vicinity of neutrality, but slightly on the acid side, and that in older compositions made according to the invention, the pH value changed towards neutral over a period of time. For example, samples showed a pH value of about 5 when first prepared, and after storage for more than a year indicated a pH of 6.5. Consequently, the pH value of the described compositions is in the area where attack on the tin lining of the cans would be minimized, and in addition to this, the compositions have the characteristic of very early forming a gray film on the tin-plated interior of the cans which does not change in character over the course of long storage.

It will be appreciated that the well-known principles of preparing aerosol compositions are applicable to the present invention. For example, the specific examples given herein are for the purpose of illustrating the invention, and it will be appreciated that the precise percentages of components which are mentioned may be varied as usual in the formulation of aerosol products.

The essential feature of the present invention resides in the combination of ingredients which make it possible to substitute a substantial amount of water for more expensive organic compounds previously used, in compositions wherein hydrolyzable components are employed. This corrosion inhibition follows from the employment of citrate and acid ions (as well as the ions and acids referred to in the specification), in combination with a tin-lined metal container. The examples disclose compositions employing about 27 to 37% water, but more or less may be employed. The advantages of the invention, it will be evident, begin at the point where any water is employed with hydrolyzable components, and the advantages in most all instances are proportionate to the amount of water that can be substituted for the more costly organic materials. In certain types of compositions, for example, window cleaners, a very substantial proportion of water may be employed along with components such as methylene chloride and trichloromonofluormethane (propellant 11) which could not be previously employed in such compositions when packaged in metal containers. In compositions of this nature up to 75% or more water is employed, so that the invention, as summarized immediately above may be successfully employed in packaging aerosol compositions containing from 1% or less of water up to 75% or more. The invention is also applicable to "foam" type aerosol products in which the proportion of fluorinated hydrocarbon propellant is relatively low, for example only 5 to 8 or 8 to 10%. In

such products, employment of the present invention enables reducing the amount of fluorinated hydrocarbon propellant down to about 2%, thus effecting a considerable saving even in products of this nature. In other products more than 50% fluorinated hydrocarbon propellant has been used and the present invention effects substantial saving even when used to cut this to about 50%. In some products which normally contain a large amount of water, for example window cleaning compositions and the like, having up to 95% water, the invention is particularly applicable, especially with respect to the feature which permits employing useful amounts of carbon dioxide as a propellant or propellant assistant. Where an acid and carbonate are employed to produce the propellant assistant in situ, as well as provide the anti-corrosion action, the combined amount of acid and carbonate may range from .5 to 20%, depending upon the pressure desired. The larger amounts may be used where high pressures are desired, for example in some commercial applications where large, strong containers are employed. As a guide in applying the invention to such various compositions as described in the foregoing parts of the specification, it is preferred to use sufficient weakly ionized acid, such as citric, to provide the composition with an initial pH value of about 5 while there is also present the ions provided by sodium citrate (or ions provided by a relatively highly ionized salt of the corresponding acid selected for use). In certain products, such as, for example, highly carbonated ones and/or those containing edible acids as phosphoric, the initial pH value may be adjusted in the range of 3.5 to 4.5, but preferably at the higher figure in such cases.

The usual practices in connection with the use of emulsifiers are applicable to the compositions described herein. For example, the emulsification of water and organic liquid phases may be greatly facilitated by employing emulsifiers sold under the trade name "Pluronic L-64," "Tween-20," "Span-20," as well as others which are presently employed. For example, the compositions described in Example 3 were made using "Tween-20" as the emulsifier. However, as explained above, the usual practices in connection with the use of emulsifiers are equally applicable here.

I claim:

1. A pressurized self-dispensing package comprising an iron container having tin on its interior, and a composition therein comprising water, at least one organic material which ordinarily produces corrosion selected from the group consisting of alcohols and halogenated hydro-

carbons which ordinarily produce corrosion due to hydrolysis, and an alkali metal salt of an aliphatic hydroxy carboxylic acid having a hydroxy group in the alpha position to the carboxylic group in an amount sufficient to inhibit corrosion by said corrosion causing material.

2. A pressurized self-dispensing package as claimed in claim 1 in which one of the materials which ordinarily causes corrosion due to hydrolysis is a halogenated hydrocarbon propellant.

3. A pressurized self-dispensing package as claimed in claim 2 in which the said propellant is a fluorinated hydrocarbon.

15 4. A pressurized self-dispensing package as claimed in claim 3 which also contains gaseous carbon dioxide, whereby complete emptying of the package may be accomplished with less fluorinated hydrocarbon propellant than would otherwise be required.

5. A pressurized self-dispensing package as claimed in claim 4 in which the alkali-metal salt is a citrate.

20 6. A pressurized self-dispensing package as claimed in claim 5 in which the alkali-metal citrate and the gaseous carbon dioxide are formed within the package by the reaction of an alkali-metal carbonate and citric acid.

25 7. A pressurized self-dispensing package as claimed in claim 6 in which the alkali-metal carbonate is sodium bicarbonate.

8. A pressurized self-dispensing package as claimed in claim 3 which, in addition to said fluorinated hydrocarbon propellant, also contains at least one organic solvent which ordinarily causes corrosion due to hydrolysis.

30 9. A pressurized self-dispensing package as claimed in claim 8 in which one of said organic solvents is methylene chloride.

10. A pressurized self-dispensing package as claimed in claim 9 in which the organic solvent phase and the aqueous phase are of substantially the same density.
